UNITED STATES PATENT OFFICE.

HAMPTON MITCHELL PRICE, OF NEW YORK, N. Y.

DESIGN FOR AN INSTRUMENT CABINET OR SIMILAR ARTICLE.

Application filed April 20, 1925. Serial No. 13,171. Term of patent 7 years.

To all whom it may concern:

Be it known that I, HAMPTON MITCHELL PRICE, a citizen of the United States, residing in New York city, borough of Manhattan, in the county and State of New York, have invented a certain new, original, and ornamental Design for Instrument Cabinets or Similar Articles, of which the following is a specification, reference being had to the accompanying drawing, which is a front perspective view of an instrument cabinet or similar article showing my new design.

I claim:

The ornamental design for an instrument cabinet or similar article as shown.

HAMPTON MITCHELL PRICE.
